DUAL TUBE PNEUMATIC LIFE PRESERVER
BELT

Edward C. Craig, United States Navy

Application February 5, 1945, Serial No. 576,351

4 Claims. (Cl. 9—19)

(Granted under the act of March 3, 1883, as
amended April 30, 1928; 370 O. G. 757)

1

This application is a continuation, in part, of the joint application of Edward C. Craig and Lloyd A. Straits, Serial No. 452,823, filed July 30, 1942.

This invention relates to a dual tube life belt and has for an object to provide a life belt of the gas cartridge type having two tubes, which tubes are adapted to be quickly filled by a single operation.

A further object of this invention is to provide a dual tube life belt having twice the flotation power of a single tube life belt, yet capable of being filled by a single operation as quickly as a life belt of the single tube type.

A further object of this invention is to provide a single operating mechanism capable of simultaneously releasing the gas from two independent gas cartridges to fill both tubes of the dual type life belt simultaneously.

A further object of this invention is to provide a dual type life belt capable of being carried in a snug fitting position about the waist of the wearer when in operative position, and having an expansion section enabling it to enlarge to a size to slide up the trunk of the wearer when inflated and in the water so as to provide the flotation support about the chest just below the arms.

A further object of this invention is to provide a dual type life belt having a single operating mechanism for simultaneously filling each tube from an independent gas pressure cartridge and also having each tube provided with an independent valve and tube of sufficient size to permit rapid oral inflation or re-inflation, as necessary, to keep the proper pressure within the tube.

Still a further object of this invention is to provide a dual type life belt provided with an independent gas cartridge operating mechanism capable of releasing the pressure from both cartridges to their tubes simultaneously and actuated by a single squeezing movement of one hand of the wearer.

Still a further object of this invention is to provide a dual tube life belt capable of easily and quickly being actuated from the deflated to the inflated position by the wearer, even after he is already in the water.

With the foregoing and other objects in view, the invention consists in the construction, combination and arrangement of parts hereinafter described and illustrated in the drawings, in which:

2

Fig. 1 is a plan view of the life belt of this invention.

Fig. 2 is an edge view of Fig. 1.

Fig. 3 is a partly sectional, fragmentary view of the pressure cartridge end of the dual tube life belt.

Fig. 4 is an end view of Fig. 3.

Fig. 5 is a top edge view of the uninflated life belt as it would appear when placed about the waist of the wearer.

Fig. 6 is a sectional view on line 6—6 of Fig. 1.

Fig. 7 is a plan view of a second form of life belt embodying this invention.

Fig. 8 is an edge view of Fig. 7.

Fig. 9 is a sectional view taken on line 9—9 of Fig. 7, and

Fig. 10 is a sectional view taken on line 10—10 of Fig. 7.

There is shown at 10 the dual type life belt of this invention, consisting of a pair of substantially identical pneumatic tubes, 11 and 12, hinged together longitudinally by a strip 13 cemented along the side thereof. Each tube 11 and 12 is so folded longitudinally in deflated position that it has a plurality of accordion pleats 14 formed therein, here shown as three in number. At spaced points along the belt there are provided pairs of male and female clip straps 15, with snap fasteners 19 for releasably holding the accordion pleats folded together in the flat position shown in Figs. 2, 5, and 6. The snap fasteners 19 on these clip straps 15 are of such strength that they will disengage whenever the tubes are expanded by pneumatic pressure, thus enabling the tubes to expand to their maximum.

In addition to each of the tubes being provided with these accordion pleats which enable them to expand transversely, the belt 10 is also provided with a transverse pleat as at 16, and adapted to be held in this transverse pleated position by means of clip straps 17 having cooperating male and female snap fastener elements 18 thereon at the outer edges of the tubes. Extending across the upper surface of the belt there is provided a pair of cooperating straps 20 having a plurality of cooperating male and female snap fastener elements 21 for releasably holding this fold of the pleat 16 in folded position. These snap fasteners on the clip straps 15, 17, and 20 are all adapted to unfasten under the force of pneumatic pressure within the tubes, this permitting the belt 10 to lengthen simultaneously with its expansion.

One end of the belt 10 is provided with a sealing strip 22. Closing off such end is a buckle

portion 23, slidably mounted over the end of the belt, and provided with a hooked tongue 24 for cooperating with a slotted tongue 25 forming part of a casing 26 fastened to the other end of the belt 10. By sliding the buckle 23 along the belt 10, the belt can be adjusted to snugly fit the waist of the wearer, even though the girth of the wearer may vary within wide limits. This casing 26 includes a pair of gas cartridge receiving cylinders 27. The end of one tube 11 is hermetically secured to one of the tubes 27 as at 28 and similarly the end of the other tube 12 is hermetically secured to the other cylinder 27, likewise as at 28.

These cylinders 27 are of such a size as to 15 slidably receive gas cartridges 30 therein. Caps 31, each provided with a cartridge puncturing point 32, are adapted to be threaded as at 33 onto the cylinder 27 and are each provided with a spring 34 for yieldably retaining the cartridge 30 away from contact with the puncturing point 32. To prevent loss of the caps 31, they are each provided with a retaining ring 35 slidably fitting about a reduced neck 36 and held to the casing 26 by a string 37. These caps 31 are knurled as at 38, permitting them to be easily removed for loading the cartridge 30 into the cylinder.

To insure the cap providing a pressure-tight fit with the cylinder, a rubber gasket 40 is held in a recess against a shoulder 41 and adapted to be contacted by the end of the cap 31.

The cylinder 27 is provided with a plurality of longitudinal ribs 42 so as to hold the cartridge centrally therewithin but provide a passageway for the gas from the punctured end of the cartridge 30 through an opening 43 in the other end of the cylinder 27 to enter into the corresponding tube (11 or 12). Extendable through opening 43 is a cammed toe 44 pivoted as at 45 and provided with a somewhat curved lever handle 46. As will be seen in Fig. 3, the lever handles 46 extend in opposite directions from each other and when caused to approach each other to the positions 46', the toes 44 extend through the openings 43 and push the cartridges 30 away from the bottoms of the cylinders so as to push their opposite ends into puncturing contact with the puncturing points 32. Upon release of pressure on lever handles 46, the springs 34 push the now punctured cartridges away from the points 32, thereby permitting the gas pressure within the cartridges to travel along the cylinders 27, through the openings 43, and into the tubes 11 and 12, to inflate the belt.

In addition to the gas cartridge for inflating each tube 11 and 12, there is provided an oral inflating means for each tube, consisting of an inflation tube 47 secured to a belt tube inlet 48 at one end thereof while the other end is provided with an oral valve 50. Inasmuch as these tubes 47 must be of sufficient length to reach from the waist to the mouth if necessary, they are held in position longitudinally of the belt 10 by means of a plurality of tunnel patches 51 through which the inflation tubes 47 extend.

In operation, the belt 10, with all the snap fasteners jointed to hold the belt in folded position, is placed about the waist of the wearer, the buckle 23 being slid along the belt to make the belt snugly fit the particular individual, and the hooked tongue 24 is secured in the slotted tongue 25. When an emergency occurs and it is desired to inflate the belt 10, the wearer places his hand about the end of the belt over the two hand levers 46, squeezes the hand levers 46 within 75

the tubes quickly towards each other, and lets go. This punctures both gas cartridges 30 and inflates both tubes 11 and 12, the pressure being sufficient to cause the snap fasteners to separate, permitting the belt to expand both transversely and longitudinally. The hinge strip 13, being on one side only, permits both tubes to inflate to their maximum capacity. This action usually takes place as the wearer is entering or has entered the water. Due to the release of the longitudinal fold in the belt 10, the diameter of the inflated belt is now sufficiently greater than the diameter of the uninflated belt as to enable the belt to slide upwardly from the waist position to a chest position and support the wearer so that his head will easily remain out of the water.

If any of the pressure should escape for any reason or should the cartridge 30 be missing or unavailable, the belt may be inflated or reinflated by means of the mouth through the oral valves 50 of the inflation tubes 47.

A further embodiment of this invention is shown in Figs. 7 through 10. In these figures the dual tube life belt 60 comprises a pair of substantially identical pneumatic tubes 61 and 62, which are secured longitudinally to each other by two strips 63, cemented in place along the opposite sides of the belt 60, as shown in Figs. 7 and 10. Each of the tubes 61 and 62 is so folded longitudinally in deflated position that it has a plurality of longitudinally extending accordion pleats 64 formed in both of its upper and lower edges, as shown clearly in Fig. 10.

The life belt is also provided with a transverse fold 65 to temporarily decrease its effective length, as shown in Fig. 8. This fold 65 is maintained releasably in position by means of straps 66 having cooperating male and female snap fastener elements 67, as shown in Figs 7 and 8. These snap fasteners 67 on the straps 66 are adapted to unfasten under the force of pneumatic pressure of the inflatable tubes 61 and 62, thereby permitting the belt to lengthen simultaneously with its expansion radially.

Each of the pleated inflatable tubes 61 and 62 is also provided with a valved tube 68 to permit its separate oral inflation. The oral inflating tubes 68 may be folded and stored in an out-of-way position under flaps 69 which are detachably secured together by means of snap fasteners 69'.

One end of the belt 60 is provided with a sealing strip 70 to hermetically seal the corresponding end of each of the inflatable tubes 61 and 62. A buckle or fastener 71 is slidably mounted over this end of the belt 60 and is adapted in adjusted position to close the inflatable tubes at that location. This belt fastener 71 is provided with a hooked tongue 72 for engagement with a slotted tongue 73 forming part of an inflating buckle device or cartridge casing 74. By sliding the fastener 71 along the length of the belt 60, the belt 60 can be adjusted to snugly fit the waist of the wearer even though the girth of the wearer may vary within wide limits.

The cartridge casing 74 serves as a buckle for the belt 60 and forms a housing for two cartridges 75 containing carbon dioxide (CO₂) or other fluid under pressure. The inflator buckle or casing 74 has an opening in one face through which the cartridges 75 may be individually inserted in place and also removed. The cartridges are retained in place in their casing 74 by means of casing lips 76 and a clip 77 which is slidable along the belt buckle or cartridge casing 74. The cartridge casing 74 has two end wall por-

tions 78, each of which is surrounded by, and has sealing relation with, the end 80 of one of the inflatable tubes 61 or 62, as shown in Figs. 7 and 9. Each of the inflatable tubes 61 and 62 may be hermetically sealed to the corresponding end wall 78 of the cartridge casing 74 by means of a clamp or strap 81.

Each cartridge 75 when installed in the casing 74 has its neck 82 extending into a recess 83 of slightly greater diameter. Each of these cartridge-neck receiving recesses 83 communicates through an orifice 84 with the corresponding inflatable tube 61 or 62.

Each cartridge 75 is adapted when positioned in the casing 74 to be punctured by means of a pin 85 operable by a movable arm or lever handle 86. The puncturing pins 85 are axially slideable in the end wall 78 of the cartridge casing 74. Each puncturing pin 85 is also in alignment with the closed mouth in the neck 82 of the adjacent cartridge 75. It is here noted that the inflator casing or buckle 74 has two depressions for receiving the two cartridges 75 and assisting in holding the cartridges so that their closed mouths are in alignment with the puncturing pins 85.

Each inner end wall 78 of the inflator buckle 74 has a bifurcated projection 87 extending into the corresponding inflatable tube 61 or 62 for pivotally supporting one of the movable arms 86. The two movable arms 86 are supported for pivotal movement toward each other, this movement being caused by grasping the belt in the hand and squeezing the belt. As the pivoted arms 86 are forced toward each other, cam toes 88 engage the headed ends 90 of the puncturing pins 85 and force the latter axially into puncturing engagement with the closed mouths of the cartridges 75. When the pivoted arms 86 are released, the pressure in the cartridges 75 is effective to expell the puncturing pins 85 and to force them into a position in which there is free discharge of the contents of the cartridges. The content of each cartridge is expelled under pressure through the orifice resulting from the puncturing operation and then through the opening 84 in the end wall 78 of the cartridge casing 74 to the corresponding inflatable tube 61 or 62 for inflating the same. Escape of the discharge of the cartridges into the atmosphere is prevented by cylindrical rubber gaskets 91, each of which provides an effective hermetic seal between the neck 82 of a cartridge 75 and the side wall of the recess which receives the cartridge neck 82.

In preparing the life belt 60 of Figs. 7 through 10 for use, the clip 77 embracing the inflator casing 74 is shifted along the same to an out-of-way position. Two cartridges 75 are then inserted in the two depressions of the cartridge casing 74. Each cartridge 75 is inserted, neck 82 first, into the cylindrical rubber gasket 91 disposed in the end wall 78 of the inflator casing 74. The other end of the cartridge is then forced into the casing depression under lip 76 and into the position shown in Fig. 9. During insertion of a cartridge 75, the rubber gasket 91 yields slightly to permit the end of the cartridge 75 to pass the casing lip 76. When a cartridge 75 is completely within a casing depression, the resilient characteristic of the rubber gasket 91 is effective to axially shift the cartridge 75 so that the inflator casing lip 76 acts to retain the adjacent end of the cartridge 75. When the two cartridges 75 are in position, the clip 77 is shifted along the cartridge casing 74 to the position of Fig. 9.

The life belt, when deflated, has the transverse fold 65 illustrated in Fig. 8 to reduce its effective length. The slide buckle or fastener 71 is also adjustable lengthwise of the belt to adapt the size of the belt to the waist of the wearer. The belt 60 is intended to be worn about the waist of an individual and to be secured in place by engagement of the hook 72 with a slot 73 in the inflator casing 74.

10 In the event of an emergency, such as when the wearer is entering the water, the belt 60 is inflated by grasping the united inflatable tubes 61 and 62 adjacent the cartridge casing 74 so that two curved pivoted arms 86 are positioned within the individual's hand. The hand is squeezed to force the pivoted arms 86 toward each other for the purpose of simultaneously camming the puncturing pins 85 through the ends of the two cartridges 75. This results in simultaneous inflation of both of the inflatable tubes 61 and 62. The discharge of each cartridge 75 necessarily flows into the corresponding inflatable tube 61 or 62.

25 The internal pressure in the two inflatable tubes 61 and 62 causes them to expand both radially and longitudinally, the longitudinal expansion resulting from release of the snap fasteners 67 and the unfolding of the belt fold 65. The expanded belt 60 then has an increased girth so that it may be repositioned under the arms of the wearer and around his chest.

30 If any of the pressure within the inflatable tubes should escape for any reason, the belt may be inflated or re-inflated by means of the mouth, through the valved oral tubes 68, which may be readily moved from their stored position under the flaps 69.

35 This being a continuation-in-part of joint application Serial No. 452,823, filed July 30, 1942, it is here stated that this sole invention includes all features which the embodiment of Figs. 7 through 10, inclusive, has in common with the embodiment of Figs. 1 through 6, inclusive. A specific form of the sole invention is that shown in Figs. 45 7 through 10, inclusive.

40 Other modifications and changes in the number and proportions of the parts may be made by those skilled in the art without departing from the nature of this invention, within the scope of 50 what is hereinafter claimed.

45 The invention described herein may be manufactured by or for the Government of the United States of America for governmental purposes without the payment of any royalties thereon or therefor.

55 What is claimed is:

1. A dual tube life preserver comprising a life belt consisting of a pair of individual tubes longitudinally joined together, means for simultaneously inflating both tubes with a pressure medium, each of said tubes being provided with a transverse fold providing overlapped portions enabling said belt to increase in girth, and means for releasably holding said fold in folded position while said belt is in deflated position, said releasable means comprising a breakable connection between said overlapped portions and being operated by the pressure medium entering into said tubes.

2. An inflatable life belt comprising a normally flat, sealed tube; means for injecting a pressure medium into said tube; the tube having portions thereof folded together to obtain compactness prior to inflation; and means releasably holding 75 said portions in folded condition and compris-

ing a connection therebetween of insufficient strength to resist the forces of expansion created by the pressure of inflation.

3. In claim 2, said holding means comprising frictionally interconnected strips secured between adjacent folded portions.

4. In claim 2, said folded portions comprising U-shaped pleats turned inwardly from the top and bottom edges of the tube and extending longitudinally thereof substantially throughout its length.
